United States Patent Office.

EDMUND YEISER, OF NEWMANSTOWN, PENNSYLVANIA.

Letters Patent No. 101,560, dated April 5, 1870; antedated March 23, 1870.

IMPROVEMENT IN THILL-COUPINGS.

The Schedule referred to in these Letters Patent and making part of the same.

To all whom it may concern:

Be it known that I, EDMUND YEISER, of Newmans-
town, in the county of Lebanon and State of Pennsyl-
vania, have invented certain new and useful Improvements
in Shaft-Boxes for Vehicles; and I do hereby
declare that the following is full, clear, and exact de-
scription thereof, reference being had to the accompa-
nying drawings and to the letters of reference marked
thereon, which form a part of this specification, in
which—

Figure 1 represents a side view of my shaft-box.
Figure 2 is a plan view of the same.

The nature of my invention consists in the construc-
tion and arrangement of a shaft-box for vehicles, in
the manner herein set forth.

In the annexed drawings—

A represents the clip, which is secured to the axle-
tree in the usual way.

The front of the clip A is supplied with the arms b b.

C designates the box, composed of the metal plate
d at bottom and adjustable plate e at top.

The two plates are bolted together, and plate d
firmly bolted to the bottom of shaft E.

The box C is embraced by arms b b, and plays ver-
tically on bolt g, which penetrates said box at its cen-
ter and binds it to arms b b.

A small space will be left between plates c and d,
which is filled with rubber, so as to admit of e being
screwed down tightly on bolt g, and thus prevent the
rattling usual with other modes of fastening.

Having thus described my invention,

What I claim, and desire to secure by Letters Pat-
ent, is—

The arrangement of plate d, cap e, and clip A, each
part constructed and operating together in the man-
ner described.

In testimony that I claim the foregoing as my own,
I affix my signature in presence of two witnesses.

EDMUND YEISER.
